UNITED STATES PATENT OFFICE.

BERTHA LEVY, OF NEW YORK, N. Y.

HATBOX.

1,405,050.

Specification of Letters Patent. Patented Jan. 31, 1922.

Application filed March 17, 1920. Serial No. 366,573.

To all whom it may concern:

Be it known that I, BERTHA LEVY, a citizen of the United States, and a resident of the city, county, and State of New York, have invented a certain new and useful Improvement in Hatboxes, of which the following is a specification.

This invention relates to a hat box particularly adapted for containing ladies' hats, and an object of this invention is to provide an article of this character which will be arranged in a particularly compact form and adapted to properly carry a hat under the most severe conditions without damage to the hat or other contents.

A further object of this invention is to provide a hat box or container which will in addition to carrying a hat be provided with means for carrying toilet articles or any other articles desired in a compact and secure manner.

A further object of this invention is to provide a hat box provided with a hat containing compartment of regulatable area so that ladies' hats with a large amount of trimming can be accommodated as readily as smaller sized hats.

With these objects and other objects which may hereinafter appear, in view, I have devised the particular arrangement and combination of parts hereinafter set forth, and more particularly pointed out in the claims appended hereto.

Reference is to be had to the accompanying drawing forming a part hereof, in which—

Figure 1 is a vertical sectional view of a hat box provided with my improvements;

Figure 2 is a plan view of the hat box;

Figure 3 is a perspective view of a portion of the shelf, showing a modified method of hinging its two halves together.

Figure 4 is a perspective view of the hat box;

Figure 5 is a plan view of a modified form of shelf showing the means for detachably securing the pockets thereto; and

Figure 6 is a sectional view on the line 6—6 of Figure 5, looking in the direction of the arrows.

Throughout the various views of the drawing, similar reference characters designate similar parts.

In the preferred embodiment of my invention, as shown in the accompanying drawing, I have disclosed a hat box of the usual cylindrical form provided with a cover 1 and a bottom 2. The shape of the hat box can be varied in many ways to suit different requirements or desires.

The cover 1 may be hinged to the box, or it may be an ordinary sliding cover adapted to be held in place by closure straps or other form of securing means. The bottom 2 of the box is provided with the hat receiving cushion 3 which is adapted to enter into the crown of the hat, and receive the hat pins to hold the hat in position thereon if it is necessary or desirable to use them.

In order that the hat may be held compactly in place without danger of being thrown loosely about the box, should it become detached from the cushion 3, I provide a clasp or clip 4 on the interior of the box on the side wall thereof, which is adapted to engage the brim of the hat. Instead of having one of these clasps 4 there may be as many as desired. Above the hat is placed a shelf 5 which is supported upon

brackets 6 secured to the inner face of the wall of the hat box. In place of these brackets 6, a continuous annular flange may be utilized for the support of the shelf 5. The brackets 6 are provided with snap fastener stud members and the shelf 5 is provided with the complementary parts of snap fasteners 8 which engage with the stud members to hold the shelf down upon its brackets 6.

The fasteners enable the shelf to be wholly or partly detached, and to be bodily adjusted to bring the opening found by either hinged section in varying positions in the box to align with the varied positions of hat trimmings. The space between the underside of the shelf 5 and the bottom of the box forms a hat-containing compartment which is regulatable in area by folding one side of the shelf so that the same overlies the other side.

The shelf is divided into parts 9 and 10, which are connected together on a central

line 11 by hinges 12. This hinging arrangement permits one of the members to be pivoted and allows the trimming of a hat in case of necessity to project upward above the shelf. The shelf 5 is provided with a plurality of pockets 7 intended to receive toilet articles or the like, and these pockets are closed by closure flaps 16 and 17. The shelf is also provided with a tape or suspending device 18 so that when desired the shelf can be bodily removed from the box and suspended on a wall or wherever desired and forms a means for holding the toilet articles at all times both in and out of the box.

10 In Figure 3 I have shown a hinge member for the two parts 9 and 10 of the shelf, comprising tabs 19 on the part 10 which have snap fastener members 20 engaging complementary snap fastener members on the part 9. This arrangement permits a pivotal movement of the two parts 9 and 10 of the shelf 5, with relation to one another and also allows them to be bodily separated when desired.

15 The box is provided with a carrying handle 22 on its side, so that the box may be carried from its side, so as to present its sometimes narrower dimension, to which form of carrying the other and associated devices are intentionally adopted; whereby the box is also relieved of the undue strain caused by carrying it from the top or cover.

20 In Figures 5 and 6, I have shown a modification of the pocket supporting shelf 5. In the arrangement shown in these figures, the pockets 7 are secured to a sheet 23 of flexible material, such as cloth, leather or the like. This sheet is adapted to be detachably secured to the face of the shelf.

25 The sheet 23 is provided with snap fastener members 24 which are adapted to engage with complementary snap fastener members 25 on the shelf 5. The sheet being of flexible material, it thus in no way interferes with the pivotal movements of the parts 9 and 10 of the shelf with respect to one another. The sheet 23 is provided at its upper and lower ends with supporting tabs 26 and 27 so that the same may be hung up when desired. When desired the sheet 23 with its attached pockets containing the various articles desired can be readily detached from the face of the shelf 5 and removed from the box without the necessity of removing the shelf from the box, and obviating the necessity of carrying the shelf which may be more or less bulky.

30 The space between the shelf and the cover of the box may be used for carrying other articles such as clothing, shoes, etc.

35 From the foregoing it will be seen that I have provided a very compact receptacle for carrying hats and toilet articles simultaneously, with the means for carrying the

toilet articles forming a complete detachable unit, and interfering in no way with the carrying of hats of various sizes.

40 In Figure 1 it will be seen that the two parts 9 and 10 can be folded to overlie one another so that trimming on a hat can, when necessary protrude up through the open space provided by the folding of the members 9 and 10.

45 From the foregoing it is obvious that my invention is not to be restricted to the exact embodiment shown but is broad enough to cover all structures coming within the scope of the annexed claims.

50 Having described my invention what I claim is:

1. A device of the class described comprising a hat box having a hat containing compartment, a detachable shelf composed of a plurality of parts pivotally connected together, said parts being bodily pivotal and adapted to overlie one another while the cover of the box is in its closed position.

55 2. A device of the class described comprising a hat box having a hat containing compartment, a shelf having a plurality of pockets, and means for detachably securing said shelf within the box.

60 3. A device of the class described comprising a hat box having a hat receiving space, supporting means in said box for receiving a shelf, a shelf adapted to be detachably secured to said supporting means and pockets on said shelf.

65 4. A device of the class described comprising a hat box having a detachable shelf, a sheet of flexible material detachably secured to said shelf and a plurality of pockets secured to said sheet.

70 5. A device of the class described comprising a hat box having a shelf supported therein, said shelf being composed of two parts, said parts being adapted to be pivoted to overlie one another while the cover of the box is in its closed position and a plurality of pockets on the two parts of the shelf.

75 6. A device of the class described comprising a hat box having a shelf supported therein and composed of two parts adapted to be pivoted with respect to one another and united together while the cover is in its closed position, and a plurality of pockets on the parts of said shelf.

80 7. A device of the class described comprising a hat box having a shelf supported therein and composed of two parts adapted to be pivoted with respect to one another, said parts being arranged to be held in overlapped position while the cover is in its closed position, and a plurality of pockets on the parts of the shelf.

85 8. A traveler's hat box containing a hat compartment in its lower part, an auxiliary

traveler's compartment in its upper part, and a removable shelf supported in said box and constituting a partition forming said compartments, said shelf having a hinged section adjustable into position to leave an opening between said compartments through which tall hat trimming of a hat stored in the lower compartment may extend into

the upper compartment, and said shelf being rotatable on its supports to bring said opening into position to receive said projecting trimming.

Signed at the city, county and State of New York this 15th day of March, 1920.

BERTHA LEVY.
